UNITED STATES PATENT OFFICE

DAVID A. NICOSIA AND HARRY SIPPEL, OF CHICAGO, ILLINOIS

RADIO CIRCUIT AND APPARATUS

Application filed March 16, 1927. Serial No. 175,659.

This invention relates to a radio circuit and apparatus for use in radio receiving sets which is of such construction that sharp tuning may be effected and wherein feed back 5 or regeneration and resulting undesirable oscillation is minimized or prevented.

It is an important object of this invention to provide an improved circuit wherein means for opposing the well-known feed back 10 effect of the output circuit on the input circuit comprises a bridge embodying concentrated adjusted impedances of high values connecting the grids of the thermionic valves with the antenna.

15 It is a further important object of this invention to provide an inductance of such form that end capacity is minimized and at the same time, high magnetic efficiency is assured.

20 It is finally an important object of this invention to provide a radio circuit, the component parts of which are so constructed and arranged as to minimize feed back and assure sharp tuning with efficient operation.

25 Other and further important objects of this invention will be apparent from the disclosures in the specification and the accompanying drawings.

The invention in a preferred form is 30 shown on the drawings and hereinafter more fully described.

On the drawings:

Figure 1 is a wiring diagram of a radio receiving circuit embodying the principles 35 of the present invention.

Figure 2 is a view similar to Figure 1 showing a slight modification of the circuit.

Figure 3 is a fragmentary side elevation 40 of the improved variable inductance used in connection with the circuit of this invention.

Figure 4 is an end elevation taken along the line IV—IV of Figure 3.

Figure 5 is an elevational view taken along the line IV—IV of Figure 3.

45 Figure 5 is an elevational view taken along the line V—V of Figure 3.

Figure 6 is a front elevation of one of the tuning dials.

50 Figure 7 is a fragmentary detail showing the method of winding the coil affording the

variable inductance shown in Figures 3 and 4.

Figure 8 is an enlarged perspective view showing the arrangement of the improved variable inductance shown in Figure 4. 55

Figure 9 is a diagrammatic side elevation illustrating the flow of magnetic lines of force in the improved inductance embodied in the present invention.

Figure 10 is a diagrammatic view showing 60 a development of the inductance illustrated in Figure 8.

Figure 11 is a side elevation showing a modified form of inductance embodying the 65 present invention.

Figure 12 is a view similar to Figure 10 showing a development of the inductance illustrated in Figure 11.

Figure 13 is a view similar to Figure 9 with 70 reference to the inductance shown in Figure 11.

Figure 14 is a side elevation illustrating another modification of the inductance embodying the principles of the present invention. 75

Figure 15 is a view similar to Figure 13 with reference to the inductance shown in Figure 14.

Figure 16 is a broken away view showing 80 a form of condenser which may be used to provide the variable adjusted capacity employed in the antenna bridge forming a part of the present invention.

As shown on the drawings:

The reference numeral 1 indicates an aerial or antenna of usual construction which is inductively coupled to a tuned radio frequency amplifying circuit embodying thermionic valves 3, 4 and 5 respectively, the output from said circuit in turn being inductively coupled to a suitable detector valve 6 in the usual manner either through additional stages of audio frequency amplification or directly to a loud speaker or similar device 7. 90

The present invention contemplates improved means for preventing undesirable feed back and resulting oscillation which is normally present in circuits of this character and comprises a bridge between the grids of the thermionic valves 3, 4 and 5 and the antenna. 100

tenna 1, said bridge being connected to the antenna at a point in advance of its connection to the primary 8 of a usual coupling transformer. The bridge above mentioned 5 comprises parallel variable adjusted condensers 9, 10 and 11 which are respectively connected to the grids of the thermionic valves 3, 4 and 5 and which in turn are connected respectively through series variable 10 resistances 9^a, 10^a and 11^a with the antenna at the point heretofore mentioned. These resistances 9^a, 10^a and 11^a are of high value, being perhaps in the neighborhood of 200,000 ohms each and are ordinarily only adjusted 15 for the characteristics of the particular circuit, the variable condensers 9, 10 and 11 being similarly only adjusted to the characteristics of the circuit and not subsequently adjusted.

20 The form of variable condenser which may be conveniently used to afford the variable adjusted capacities 9, 10 and 11 is shown in Figure 16 and comprises a base 12 which is provided with terminals 13 and 14 and which 25 supports an outer metallic cylinder 15, a dielectric 16, and a vertically adjustable inner metallic member 17. The inner metallic member 17 is internally threaded and supported by a screw 18 so that rotation of said member 17 relative to said screw effects a 30 vertical movement of the inner metallic member 17 and consequently varies the capacity afforded by the condenser. The inner metallic member 17 is connected with the terminal 35 14 through the screw 18 and the outer metallic member 15 is connected with the terminal 13.

40 In Figure 2, we have illustrated a slight modification of the circuit embodying the principles of the present invention wherein 45 the variable capacities 9, 10 and 11 are connected with the grids of the aforementioned valves 3, 4 and 5 in the manner described in the circuit illustrated in Figure 1 but wherein variable high value resistances 9^b, 10^b and 50 11^b are connected to said capacities in parallel with each other and to the antenna 1 through a common conductor 19. It will be seen that in this circuit the impedance to the feed back or oscillation is not cumulative as 55 in the circuit shown in Figure 1 but is individual to each thermionic valve, thus permitting of a somewhat more delicate initial calibration and being somewhat more efficient, although we have found the circuit illustrated in Figure 1 to operate with a high degree of satisfaction in most instances.

60 This invention further provides an improved inductance for use in tuning the same comprising in its preferred form a toroidal formed coil 20 which gradually decreases in axial diameter from the filament terminal to the grid terminal. A form of coil embodying this construction is shown in Figures 5 to 9 inclusive, of the drawings, and comprises a conductor 21 wound about a suitable

support 22 preferably of insulating material, the support being so arranged that the small end of the coil is brought adjacent the large end of the coil, the normal magnetic field about the axis being substantially as indicated by the dotted lines in Figure 9. By using a toroidal formed coil, magnetic leakage and interference is to a large extent eliminated but in the use of toroidal coils of a constant axial diameter, difficulty has been experienced with end capacity and also with the undesirable feature of the resonance points of a large number of the short wave lengths occurring close together near the grid end of the coil. By providing a coil of the form which we have invented, this end capacity from the grid to the filament is greatly reduced and the short wave length resonance points at the grid end of the coil are spaced farther apart along the axis of the coil thus facilitating tuning and the selection of short wave length stations, the wave lengths of which may be somewhat close together.

90 The improved coil embodying the present invention may be conveniently mounted on a suitable support 23 which in addition to supporting the coil affords a bearing for a shaft 24 which carries a contact member 25 normally held in contact with the end turns of the coil 20 by means of a spring 26 engaged between the support 23 and an axle 27 on the shaft 24. Said shaft 24 is also journaled in a suitable panel 28 and has a handle 29 with a pointer 30 cooperating with a dial 31 secured to its outer end outside said panel 28. Co-axial with the shaft 24 and secured to the inner face of the panel 28 is a toothed annulus 32 and secured to the shaft 24 is a locking pawl 33 which is adapted to be held in engagement with said toothed annulus when the contact member 25 is in adjusted position. This construction provides in effect a lockable adjustment which may be released by pushing in on the knob 29 to release the locking pawl 30 and the contact member 25 to permit the shaft and the contact member 25 to be turned. When the contact member 25 is moved to the desired adjusted position, the handle or knob 29 is released whereupon the spring serves to lock these parts in an adjusted position with the contact member 25 engaging the proper end turn of the coil 20 and the locking pawl 33 locking between the proper teeth in the annulus 32.

110 While the form of coil illustrated in Figures 5 to 10 inclusive, has proven to be the most desirable form, it is obvious that other forms of coils embodying the present invention might be employed which would approximate the results which we attain through the use of the coil herein described. For example, in Figures 11 to 13 inclusive, we have shown a form of coil which is separated

into two parts, each of which are of constant 5
ly decreasing axial diameter from the filament connection 34 to the grid connection 35. The flow of the magnetic lines of force in a
coil of this type is illustrated in Figure 13, a
development being shown in Figure 12, and
it will be obvious that this form of coil
achieves some of the desirable results of the
toroidal form of coil and at the same time
10 eliminates excess end capacity.

A coil such as illustrated in Figure 14 and
15 may also be employed in the circuit of this
invention, it being noted that this coil essentially
15 comprises two parts 36 and 37 respectively,
of large and small axial diameter, the
part 36 being connected to the filament terminal
20 at 38 and the small part 37 being connected
to the grid terminal at 39, the flow of the
magnetic lines of force in this type of coil is
diagrammatically shown in Figure 15.

It will be obvious that this invention provides
a radio circuit and apparatus wherein
undesirable feed back or regeneration effects
are prevented by the antenna bridge embodying
25 high value impedances consisting of the
condensers 9 and the resistances 9^a or
condensers 9 and the resistances 9^b connected in
the manner heretofore described. These
high value impedances are made adjustable
30 so that they may be calibrated to the desired
value, and once calibrated for the particular
circuit for which they are used, the desired
results are attained thereby in a superior
manner.

35 The improved coil which we have provided
assures sharp tuning and in the preferred
form, the magnetic losses and interference
are exceedingly low.

We are aware that many changes may be
40 made and numerous details of construction
may be varied through a wide range without
departing from the principles of this invention,
and we therefore do not purpose limiting
45 the patent granted hereon, otherwise than
necessitated by the prior art.

We claim as our invention:

1. In a radio circuit, an antenna, a tuned
50 amplifying circuit including parallel thermionic
valves connected to said antenna, and
parallel impedances of high value connected
to the grids of said thermionic valves and to
the antenna at a point in advance of its connection
55 to said amplifying circuit.

2. In a radio circuit, an antenna, a tuned
55 amplifying circuit including parallel thermionic
valves connected to said antenna, and
parallel impedances of high value each including
a variable condenser connected to the
60 grids of said thermionic valves and to the
antenna at a point in advance of its connection
to said amplifying circuit.

3. In a radio circuit, an antenna, a tuned
65 amplifying circuit including parallel thermionic
valves connected to said antenna, parallel
impedances of high value connected to

the grids of said thermionic valves and to
the antenna at a point in advance of its connection
70 to said amplifying circuit, and toroidal transformer coils connected in the
input circuit of each of said thermionic
valves.

4. In a radio circuit, an antenna, a tuned
75 amplifying circuit including parallel thermionic
valves connected to said antenna, parallel
impedances of high value connected to
the grids of said thermionic valves and to the
antenna at a point in advance of its connection
80 to said amplifying circuit, and variable
toroidal coils connected in the input circuit
of each of said thermionic valves.

5. In a radio circuit, an antenna, a tuned
85 amplifying circuit including parallel thermionic
valves connected to said antenna, parallel
impedances of high value connected to
the grids of said thermionic valves and to the
antenna at a point in advance of its connection
90 to said amplifying circuit, and toroidal
coils of constantly decreasing axial diameter
from the filament terminal to the grid terminal
connected in the input circuit of each of
said thermionic valves.

6. In a radio circuit, a thermionic valve
95 including a grid and a filament, and a toroidal
inductance connected between said grid and
said filament, said inductance being of
constantly increasing axial diameter from the
grid connection to the filament connection
thereof.

7. In a radio circuit, a thermionic valve
100 including a grid and a filament, a variable
toroidal inductance connected between said
grid and said filament, said inductance being
of constantly increasing axial diameter from the
grid connection to the filament connection
105 thereof.

8. In a radio circuit, an antenna, a tuned
110 amplifying circuit including a thermionic
valve connected to the said antenna, and a
resistor in series with a condenser connected
to the grid of the said thermionic valve and
to the antenna at a point in advance of its
connection to the said amplifying circuit.

9. In a radio circuit, a multi-electrode thermionic
valve, a toroidal inductance connected
115 between the grid and filament electrodes of
said valve, said inductance being of constantly
increasing axial diameter from the grid
terminal to the filament terminal, a condenser,
the said condenser being connected in shunt
120 with the said toroidal inductance, and switch
means in series circuit association with the
said condenser and the said inductance to
vary the amount of inductance shunted by
the said condenser.

In witness whereof, we have hereunto subscribed
125 our names at Chicago, county of Cook
and State of Illinois.

HARRY SIPPEL.
DAVID A. NICOSIA.
